DESCRIPTION

U.S. PATENT DOCUMENTS

FIG. 1 is a front elevation of a bottle for use with a pump dispenser showing my new design;

D. 195,368	*	6/1963	Koenigsburg	.....	D9/565
D. 221,133		7/1971	Wikke	.....	D9/537
D. 250,601		12/1978	Pick et al.	.....	D9/526
D. 253,036		10/1979	Meyer et al.	.....	D9/543
D. 253,630	*	12/1979	McCredie	.....	D9/543
D. 288,528	*	3/1987	Parad	.....	D9/526
D. 340,217		10/1993	Delage et al.	.....	D9/543
D. 382,803		8/1997	Gavin	.....	D9/529
D. 392,890		3/1998	Zaksenberg	.....	D9/529
D. 398,244	*	9/1998	Bertolini et al.	.....	D9/565

FIG. 2 is a rear elevation thereof;

FIG. 3 is a left side elevation thereof;

FIG. 4 is a right side elevation thereof;

FIG. 5 is a top plan view thereof; and,

FIG. 6 is a bottom plan view thereof.

The broken lines showing a pump dispenser in the drawings are for illustrative purposes only and do not form part of the claimed design.
